[57] CLAIM

The ornamental design for a picture frame bracket, as shown and described.

DESCRIPTION

FIG. 1 is a perspective view of a picture frame bracket in use showing our new design;

FIG. 2 is a front perspective view thereof;

FIG. 3 is a top view thereof;

FIG. 4 is a front view thereof;

FIG. 5 is a rear view thereof;

FIG. 6 is a right side view thereof; and,

FIG. 7 is a left side view thereof.

The broken line showing of a frame, hanging wire and one frame bracket is for illustrative purposes only and forms no part of the claimed design.

FIG. 1

FIG. 2

FIG. 3

FIG. 4
